UNITED STATES PATENT OFFICE

RYAN SADWITH, OF NEWARK, NEW JERSEY

DRIER

Application filed November 13, 1929. Serial No. 406,735.

This invention relates to a drier.

In various trades such as metal lithography, printing or coating on tin plate and other branches of the printing trade wherein metallic plates are used during various of the processes it becomes necessary to subject the metallic plates to a proper heat treatment and drying. Various mechanical driers have been invented but in the use of mechanical drying great difficulty has been found in the proper distribution of the air, in the proper control of the heat and in the proper control of the volume and quantity of heat. In most driers the plates are carried by hooks or bales supported by a travelling carrier which passes through the drier. These bales or hooks are relatively close together so that it is difficult to secure an even distribution of the drying air between the relatively close positioned plates while they are in motion in the drier on the carrier. The conditions of the industry generally require open ended driers and the infiltration of the room air makes the control of the hot air within the drier uncertain. In the usual form of drier the temperature may be controlled but the temperatures of one zone will always have approximately the same relationship with that of another zone. In other words, if a curve of the heat is plotted the curve will be of the same shape regardless of the temperature for the drier. This is disadvantageous as certain plates may require a relatively high heat followed by a slowly descending temperature or followed by a constant temperature. Again other plates may require a relatively low initial temperature of heat treatment followed by an ascending temperature or a constant temperature. Still other forms of plates may require alternate zones of relatively high and low temperatures.

One of the objects of this invention is to provide a drier for metallic plates wherein the drying air is properly distributed over the metal plates.

Another object of the invention is to provide a drier wherein the temperature of one section of the drier may be had independently of other sections. A further object of the invention is to provide a drier having means

to independently control the temperatures of the different sections of the drier.

A further object of the invention is to provide a drier wherein the volume and quantity of the drying air may be controlled.

A still further object of the invention is to provide a drier wherein the volume and quantity of drying air may be sectionally controlled, each section independent of the other.

Still another object of the invention is to provide a drier that is open at each end wherein the infiltration of room air is reduced to a minimum.

Still another object of the invention is to provide a more efficient and economical drier.

Referring to the drawings:

Figure 1 is a longitudinal sectional view of a device embodying the principles of my invention.

Figure 2 is a sectional view of Figure 1 along the line 2, 2, looking in the direction of the arrows.

Figure 3 is a sectional view along the line 3, 3, of Figure 1, looking in the direction of the arrows.

Figure 4 is a cross sectional detailed view of the plenum inlet duct showing the damper control.

Figure 5 is a longitudinal detailed sectional view of the plenum inlet duct showing the damper control governing the admission of the air to the drying chamber.

Figure 6 is a plan view of Figure 5.

In carrying out my invention I propose to provide a housing 1, having an outer covering 2, of heat insulating material. Housing 1 has open ends 3 and 4 and is supported by legs 5 and 6. Air spills 7 and 8 are located adjacent the end openings 3 and 4 in the roof of the housing 1. Within housing 1, I provide a plate conveyor which conveyor consists of endless chains 9, 10, carrying hooks or bales 12, and driving sprockets 13, 14, which move the chains 9, 10. Sprockets 13, 14, are journaled upon driving shafts 15 and 16 which may be driven by belting or gearing in the well known manner. Idler wheels, or as shown tracks 11, support the chains 9, 10, between sprockets 13 and 14. Within housing 100

1 at the bottom thereof I provide plenum (inlet) air chambers 17, 18, 19, 20, 21, 22, which are of unique construction and design. Each chamber 17, 18, 19, 20, 21 and 22, is an interchangeable section, easily cleaned, removable and having exterior control of the dampers for each section. The roof 23 of each section has openings therein, a damper 24 having similarly shaped and correspondingly positioned openings therein is adapted to slide on roof 23 of each chamber to open or partially open to the desired degree the openings formed by the coinciding or partial coincidence of the openings in the roof 23 of each chamber and the openings of damper 24. The positioning of dampers 24 is governed by test and they can then be set initially for even distribution of air and require no further adjustment. Dampers 24 are controlled by rod 25 terminating externally of housing 1 in handle 26. Within housing 1 are chambers 27, 28, 29, 30, 31, 32, corresponding in number and position with chamber 17, 18, 19, 20, 21, 22. Within chambers 27, 28, 29, 30, 31 and 32, are dampers 33, similar in every respect to dampers 24 except they operate on the floor of the chamber and not the roof. Dampers 33 are likewise controlled by rod 34 terminating in handle 35 outside of housing 1. To each plenum or inlet chamber 17, 18, 19, 20, 21, 22, is led hot air inlet duct 36, 37, 38, 39, 40, 41, respectively, having individual dampers 42, 43, 44, 45, 46, 47, in each duct to control the quantity of heated air to be delivered to each chamber, these dampers can be manually or thermostatically controlled as desired. Ducts 36, 37, 38, 39, 40, 41, lead from a common supply duct 48 which takes its supply of heated air from a recirculation fan 49 of the pushing and pulling type which is run at a constant speed. To each exhaust air chamber 27, 28, 29, 30, 31, 32, is led an exhaust air duct 50, 51, 52, 53, 54, and 55, respectively. Dampers 6 are in each duct to control the quantity of air exhausted from the chambers by the fan 49. These dampers may be manually or automatically operated by thermostatic control. Exhaust ducts 50, 51, 52, 53, 54 and 55, lead to a common duct 57 which in turn empties into fan intake 58 of fan 49. Also connected to the fan intake 58 is pipe 59 from heater 60. A damper 67, is in pipe 65 to control the amount of fresh hot air that shall be added to maintain the proper temperatures in the drier. The heater has a maximum temperature control through thermostat 61 positioned in pipe 59, and through thermostat 62 positioned inside heater 1.

60 The operation is as follows: Fan 49 takes the exhaust air mixed with the proper quantity of fresh heated air to raise the exhaust air to the necessary and desired temperature and drives it through duct 48 where it is fed to ducts 36, 37, 38, 39, 40, 41, past dampers 42, 43, 44, 45, 46, 47, to chambers 17, 18, 19, 20, 21, 22, past dampers 24 up through and between the plates 69 supported by hooks 12 on chains 9, 10, thence through exhaust dampers 33 in the chambers 27, 28, 29, 30, 31, 32, each corresponding to the chamber directly below it. The exhaust air is exhausted past dampers 56 in each duct 50, 51, 52, 53, 54, and 55, to and through duct 57 to intake 58 of fan 49 where it has again mixed with fresh hot air from heater 60. It is desirable that the pressure in the drier housing 1 be slightly greater than atmospheric to prevent too great an infiltration of air into the drier at the open ends 3 and 4. Air spills 7 and 8 cause an up draft carrying with the heated air most of the infiltration air and prevent the workmen from becoming annoyed by the heated gases that would otherwise escape from the ends 3 and 4.

65 It will thus be seen that the proper distribution of the heated air and the control of the quantity and temperature is accomplished by the zone division of the plenum or inlet chambers and the corresponding zone division of the exhaust chambers within the drier with the damper control of the zones outside of the housing to control the static pressure in the plenum chambers and the static suction of the exhaust chamber and thereby to control the pressure between the plenum chamber and the exhaust chamber in each section of the heater.

70 It will further be seen that the individual chambers controlled by the sliding dampers control the volume of the air in each section of the drier. The temperature is controlled by the temperature of air taken from the heater and mixed with the exhaust air. This is accomplished by thermostatically regulating the burners. The re-use of the exhaust air with the addition of only a small quantity of air at relatively high heat from the heater permits of a more economic operating cost. The temperatures in this form of drier range from 180° to 400°. With such a zone system the temperature, volume of air and distribution is variable within the drier for any section since each section can be regulated independently by independent controlling means either manually or thermostatically as desired.

What I claim is:

1. A drier for metal lithographic plates or the like comprising an open end housing hav-

- ing a single open end compartment lengthwise thereof, a source of drying medium, a plurality of plenum chambers within and at the top of said housing, said source of drying medium severally connected to each of said chambers, means for controlling the quantity and velocity of drying medium to each of said chambers, outlets from said chambers to the interior of said drier, corresponding outlet chambers to said plenum chambers, said outlet chambers positioned within said drier at the top thereof, openings from the interior of said drier to said outlet chambers, a circulation fan for said drying medium, connections from said chambers and said circulation fan. 70
2. A drier for metal lithographic plates or the like comprising an open end housing having an open end single drying compartment lengthwise thereof, a source of drying medium, a circulation fan for said drying medium, a plurality of plenum chambers within and at the bottom of said housing, a manifold connection between said circulation fan and each of said plenum chambers, means for controlling the quantity of drying medium flowing out of said ducts to said plenum chambers, outlets from said chambers to the interior of said drier, sliding dampers to control the heating medium passing through said outlets, outlet chambers corresponding to said plenum chambers, said outlet chambers positioned within said drier at the top thereof, openings from the interior of said drier to said outlet chambers, sliding dampers to control the drying medium for said outlet chamber openings, manifold connections from each of said outlet chambers to said circulation fan. 80
3. A drier for metallic plates and the like, comprising a housing, a circulation fan for a drying medium, sectional plenum chambers within said housing at the bottom thereof, corresponding outlet chambers within said housing at the top thereof, a source of drying medium, a conduit from said source of drying medium, said conduit terminating in a manifold with connections to each of said plenum chambers, openings from said plenum chambers to the interior of said drier, outlet chambers within said drier at the top thereof, said outlet chambers being sectional and corresponding in position and number to said plenum chambers, openings in said outlet chambers to communicate with the interior of said drier, an outlet manifold connecting with each of said outlet chambers and communicating with said circulation fan. 90
4. A drier for metallic plates and the like, comprising a housing, sectional plenum chambers within said housing at the bottom thereof, corresponding outlet chambers within said housing at the top thereof, a source of drying medium, a conduit from said source of drying medium to a mixing chamber, a mixing chamber on the intake side of a circulation fan, a duct from the outlet side of said circulation fan terminating in a manifold connecting to each of said plenum chambers, dampers in each manifold connection, openings from said plenum chambers to the interior of said drier, dampers for said openings, outlet chambers within said drier at the top thereof, said outlet chambers being sectional and corresponding in position and number to said plenum chambers, openings in said outlet chambers to communicate with the interior of said drier, dampers for the openings of each of said outlet chambers, an outlet manifold connecting with each of said outlet chambers and terminating in a duct connected to said mixing chamber of said circulation fan. 100
5. A drier for metallic plates and the like, comprising a housing, a circulation fan for the drying medium, removable, individual, sectional plenum chambers within said housing at the bottom and lengthwise thereof, inlet ducts communicating with said plenum chambers and with said circulation fan, dampers within each of said ducts, openings from each of said ducts to the interior of said housing, dampers for said openings for each of said plenum chambers, corresponding outlet chambers within said drier, each corresponding outlet chamber positioned at the top of said drier directly over its corresponding plenum chamber, openings in said outlet chambers to the interior of said housing, dampers for said openings in said outlet chambers, exhaust ducts communicating with each of said outlet chambers and with said circulation fan, separate dampers in each of said exhaust ducts. 110
6. A drier for metallic plates and the like, comprising a housing having an open end, a circulation fan to circulate a drying medium, said housing having a plurality of plenum chambers within said housing at the bottom thereof and lengthwise of the drier, ducts from said fan for supplying to each of said plenum chambers said drying medium, means for independently controlling the quantity of said drying medium to each of said chambers, outlets from said plenum chambers to the interior of said housing, means for controlling and distributing the flow of heating medium from said chambers to the interior of said housing, outlet chambers corresponding in number and position with said plenum chambers and positioned at the top of said housing, means for controlling the distribution and quantity of the heating medium from the interior of said drier to the interior of said outlet chambers, ducts for conducting the exhaust heating medium from said outlet chambers to said circulation fan. 120
7. A drier for metallic plates and the like, comprising a housing having an open end, a

- fan for circulating a drying medium, air spills in the top of said drier at each end, said housing having a plurality of plenum chambers within said housing at the bottom thereof; ducts from said fan for supplying to each of said plenum chambers drying medium, and means for independently controlling the quantity of said drying medium to each of said chambers, openings from said plenum chambers to the interior of said housing, means for controlling and distributing the flow of heating medium from said chambers to the interior of said housing, outlet chambers at the top of said housing, means for controlling the distribution and quantity of the heating medium to the interior of said chambers, a mixing chamber on the intake side of said circulation fan, ducts for conducting the exhaust heating medium from each of said outlet chambers to said mixing chamber and a conduit to said mixing chamber from a source of heated drying medium.
8. A drier for drying metallic plates and the like, comprising a housing open at both ends, spills in the top thereof adjacent each end, a fan, a heater supplying heated air to mixing chamber, a mixing chamber on the intake side of said fan, a damper between said heater and said mixing chamber to control the quantity of heated drying medium to said fan, means for controlling the maximum temperature of the drying medium delivered to said mixing chamber, exhaust ducts delivering to said mixing chamber whereby the exhausted air is mixed with the additional heated air from said heater and delivered by said fan to a hot air duct, said hot air duct terminating in a manifold, each of the arms of said manifold communicating with separate, individual, removable plenum chambers within said housing, openings from said plenum chambers communicating with the interior of said housing, exteriorly operated dampers for said openings, individual, removable outlet chambers within said housing and at the top thereof, openings from the interior of said housing to said outlet chambers, dampers exteriorly operated for said openings, said exhaust ducts leading from said outlet chambers to said mixing chamber to permit of the recirculation by the fan after the addition of the requisite additional drying medium from said heater.

Signed at New York in the county of New York and State of New York this 17th day of October A. D. 1929.

RYAN SADWITH.
